CLAIM

The ornamental design for a display screen with animated graphical user interface, as shown and described.

DESCRIPTION

FIG. 1 is a front view showing a first image in a sequence of an embodiment of a portable computerized device showing our new design;

FIG. 2 is a front view showing a second image in a sequence of the embodiment of the portable computerized device showing our new design;

FIG. 3 is a front view showing a third image in a sequence of the embodiment of the portable computerized device showing our new design;

FIG. 4 is a front view showing a fourth image in a sequence of the embodiment of the portable computerized device showing our new design; and,

FIG. 5 is a front view showing a fifth image in a sequence of the embodiment of the portable computerized device showing our new design.

Any features shown with broken lines are for environmental purposes only and form no part of the claimed design.

The appearance of transitional images sequentially transitions between the images shown in FIGS. 1-5. The process or period in which one image transitions to another image forms no part of the claimed design.
